Patented Oct. 25, 1927.

1,646,382

UNITED STATES PATENT OFFICE.

JOHN H. BAKER, OF DETROIT, MICHIGAN.

BOILER.

Application filed December 11, 1923. Serial No. 679,936.

My invention relates to a new and useful improvement in a boiler adapted for use particularly with vehicles in which steam is used as the driving power, and has for its object the provision of a boiler of this class which will be simple in structure, economical of manufacture and highly efficient in use.

Another object of the invention is the provision of a boiler of this class which will possess a maximum amount of flexibility.

Another object of this invention is the provision of a boiler having water tubes mounted in sections which may be removed and replaced at will, thus regulating the capacity of the boiler without disturbing the frame work or foundation of the boiler.

Another object of the invention is the provision of headers connected to a steam dome and carrying water tubes which are bellied or formed sinuous intermediate their ends to provide for the expansion and contraction of the tubes under different conditions of temperature so as to prevent injury to the boiler because of variations in temperature.

Other objects will appear hereinafter.

The invention will be best understood from a reference to the accompanying drawings which form a part of this specification, and in which,

Fig. 1 is an end elevational view of the invention,

Fig. 2 is a side elevational view of the invention,

Fig. 3 is a top plan view of the invention, and,

Fig. 4 is a sectional view taken on substantially line 4—4 of Fig. 1.

The invention in its preferred form comprises a plurality of sections, each section having a header 7 and a header 8 connected with pipes having the portions 9 and 10 bent as at 11. If desired these pipes may be formed with a number of bends intermediate their lengths to provide a sinuous arrangement. Projecting from each end of the headers 8 are nipples 12 which are connected to a pipe 13 by means of a union 14, the pipes 13 being curved as shown and attached in communication with a steam dome 15. These domes are positioned over the headers 8, and additional domes 16 and 17 are also positioned on the headers 8. These several domes are connected to each other by means of the pipes 18, 19 and 20, the steam

outlet pipe 21 being connected to the pipe 19.

Supporting the headers is a frame or housing 22 in which is positioned a suitable heating element 23 having a pilot element 24, the structure of the heating element being no part of this invention and therefore not described in detail. Heating elements in boilers of this class are well known. A water feed pipe 25 is provided, this pipe 25 being provided with a pipe 26, having an angularly turned portion 27 and coupled to a nipple which projects from the header 7 by means of a coupling 29. One of these pipes is provided for each header and serves to connect each header in communication with the water feed pipe. If it is desired to remove one of the headers or to use a less number of headers than there are connecting pipes 26, the angularly turned portion may be provided with a suitable cap or plug.

A safety valve 30 is connected to one of the steam domes, and a drain pipe 31 is attached to the steam dome and to the feed water pipe 25. As shown in Fig. 4 the pipes connecting the headers are staggered relatively to adjacent headers so that the hot gases passing from the heating element are deflected by the water tubes.

In use any number of sections, within the capacity of the steam domes and water feed pipes may be used, the removal or replacement of the sections being a very easy and simple operation, owing to the method of attaching the sections to the domes and the feed pipe. In this way the capacity of the boiler may be regulated with a resultant saving of fuel in operation. The entire structure of the boiler and particularly the bending of the water tubes, as shown, renders a maximum amount of flexibility to the boiler, which is highly desired in boilers of this class and used for this purpose. The staggering of the tubes of adjacent sections also affords a greater heating surface coming into direct contact with the hot gases.

While I have illustrated and described the preferred form of structure I do not wish to limit myself to the details of structure set forth but desire to avail myself of such variations and modifications as come within the scope of the appended claims.

Having thus described my invention what I claim as new and desire to secure by Letters Patent is:

1. A sectional boiler of the class described,

- comprising a row of steam domes, adjacent domes being connected in communication with each other; a feed water pipe; a plurality of headers extending transversely of said domes and arranged in sets of pairs, the upper header of each pair being in close proximity to said domes, and the other being spaced therefrom; a plurality of bow-shaped pipes connecting the headers in each set; individual connection between each of the lower headers and said feed water pipe; and individual connection for each end of each of the upper headers connected to the outermost of said domes.
15. 2. A sectional boiler of the class described, comprising a row of steam domes, adjacent domes being connected at one end in communication with each other; a feed water pipe; a plurality of headers extending transversely of said domes and arranged in sets of pairs, the upper header of each pair being in close proximity to said domes and the other being spaced therefrom; a plurality of bow-shaped pipes connecting the headers in each set; an individual connection between each of the lower headers and said feed water pipe; and an individual substantially **U**-shaped connection for each end of each of the upper headers connecting to the outermost of said domes.
30. 3. A sectional boiler of the class described comprising a row of steam domes, adjacent domes being connected in communication with each other at one end with a substantially **U**-shaped connecting member; a feed water pipe; a plurality of headers extending transversely of said domes and arranged in sets of pairs, the upper header of each pair serving as a support for said domes and the other header being spaced therefrom; a plurality of bow-shaped pipes

connecting the headers in each set; an individual connection between each of the lower headers and said feed water pipe; a substantially **U**-shaped individual connection for each end of the upper headers connecting to the outermost of said domes; a supporting platform for the lowermost of said headers, said headers engaging the upper surface of said platform and said feed water pipe being projected along one side of said platform below the upper surface thereof.

4. A sectional boiler of the class described comprising a plurality of steam domes arranged in parallel relation to each other, adjacent domes being connected at one end in communication with each other; a plurality of headers extending transversely of said domes and arranged in sets of pairs, the upper header of each pair being in close proximity to said domes, and the lower header in each pair being spaced therefrom; a plurality of bow-shaped pipes connecting the headers in each set; a feed pipe; a pipe for connecting each of said lower headers individually with said feed pipe, said connecting pipes having their axes in the same vertical plane as the axis of the headers with which connected; and an individual substantially **U**-shaped connection for each end of the upper headers connecting said headers individually to the outermost of said domes, said **U**-shaped connections lying in the vertical axial plane of said headers, the upper headers being free from direct connection with each other, and the lower headers being free from direct connection with each other.

In testimony whereof I have signed the foregoing specification.

JOHN H. BAKER.
